(57) **CLAIM**

The ornamental design for a cap, as shown and described.

DESCRIPTION

FIG. 1 is a top perspective view of a cap in accordance with our new design;

FIG. 2 is a top plan view thereof;

FIG. 3 is a front elevational view thereof, a rear elevational view being a mirror image thereof;

FIG. 4 is a right-side elevational view thereof, a left-side elevational view being a mirror image thereof; and,

FIG. 5 is a bottom plan view thereof.

The broken lines depict portions of the cap that form no part of the claimed design.

1 Claim, 3 Drawing Sheets
